UNITED STATES PATENT OFFICE.

NELSON H. PATNO, OF BOSTON, MASSACHUSETTS.

DESIGN FOR A BOTTLE.

40,500.

Specification for Design.

Patented Feb. 8, 1910.

Application filed November 5, 1909. Serial No. 526,477. Term of patent 7 years.

To all whom it may concern:

Be it known that I, NELSON H. PATNO, a citizen of the United States, residing at Boston, county of Suffolk, and State of Massachusetts, have invented a new, original, and ornamental Design for a Bottle, of which the following is a specification, reference being had to the accompanying drawing, forming part thereof.

The figure is a perspective view of a bottle showing my design.

The bottle embodying the design comprises the bell shape portion A and the handle portion B, said handle being connected to the bell shape portion A by the

sleeve or collar portion C. Said bottle is symmetrical with respect to its longitudinal axis in all planes passing through that axis so that the figure of the drawing represents the bottle viewed from any point in the same horizontal plane at the same distance from the longitudinal axis.

I claim:

The ornamental design for a bottle as shown and described.

NELSON H. PATNO.
